CLAIM

(22) Filed: **Jun. 17, 2014**

The ornamental design for a smart phone case with credit card slot, as shown and described.

(51) **LOC (10) Cl. 03-01**
(52) **U.S. Cl.**

DESCRIPTION

USPC **D3/218**

(58) **Field of Classification Search**

FIG. 1 is a front isometric view of the smart phone case with credit card slot which embodies my design;

CPC A45F 5/00; A45F 5/02; A45F 5/021;

FIG. 2 is a rear isometric view thereof;

A45F 5/022; A45F 2005/00; A45F 2005/008;

FIG. 3 is a front isometric view thereof, with the flap shown open;

A45F 2005/02; A45F 2200/05; A45F

FIG. 4 is a front isometric view thereof, showing the new design in a position of use;

2200/0516

FIG. 5 is a front view thereof;

USPC D3/218–219, 215, 201, 224, 226, 228,

FIG. 6 is a rear view thereof;

D3/247–248, 269, 303; 224/240–241, 245,

FIG. 7 is a top plan view thereof;

224/578, 674, 676–681, 901, 904; 206/305,

FIG. 8 is a bottom plan view thereof;

206/320, 576, 759, 762; 455/575.1–575.8;

FIG. 9 is a right side view thereof; and,

D14/248, 250–251

FIG. 10 is a left side view.

See application file for complete search history.

The broken line showing of environment in the drawings is included for the purpose of illustrating only and forms no part of the claimed design.
